DESCRIPTION

FIG. 1 is a right perspective view of a first embodiment of a door handle for a vehicle according to my novel design;

FIG. 2 is a left perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and

FIG. 8 is a left side view thereof.

FIG. 9 is a left perspective view of a second embodiment of the door handle for a vehicle according to my novel design;

FIG. 10 is a right perspective view thereof;

FIG. 11 is a front view thereof;

FIG. 12 is a rear view thereof;

FIG. 13 is a top view thereof;

FIG. 14 is a bottom view thereof;

FIG. 15 is a left side view thereof; and,

FIG. 16 is a right side view thereof.

The broken lines are for illustrative purposes only and form no part of the claimed design.
